Specification for Design.

Patented May 25, 1920.

Application filed December 16, 1918. Serial No. 267,057. Term of patent 7 years.

To all whom it may concern:

Be it known that I, GEORGE HENRY BERWICK, subject of the King of Great Britain and Ireland, residing at 10 and 12 Adelaide road, Hampstead, in the county of London, England, have invented a new, original, and ornamental Design for Carving-Dishes, of which the following is a specification, refer-

ence being had to the accompanying drawing, forming part thereof.

The figure is a perspective view of a carving dish, showing my new design.

I claim:

The ornamental design for a carving dish, as shown.

GEORGE HENRY BERWICK.
